STRIP STOCK FEEDING AND GAUGING

Magnus E. Widell, Cincinnati, Ohio, assignor to
American Can Company, New York, N. Y., a
corporation of New Jersey

Application March 27, 1934, Serial No. 717,674

9 Claims. (Cl. 164—89)

The present invention relates to an apparatus for feeding and blanking strip stock or the like and has particular reference to the control of the stock so that it is at all times in proper position for the blanking operation.

An object of the present invention is the provision of strip handling devices for a blanking press or the like which evenly withdraw strip material from a reel, which feed the strip to the press in accordance with its blanking requirements and which maintain an amount of strip material within limits between the reel and the press so that unevenness of feeding is avoided and high speed operation is effected.

Another object of the invention is the provision of variable speed withdrawing devices for strip stock which are regulated in accordance with the requirements of a press or other machines using this stock.

A further object of the invention is the provision of gauging elements operated in connection with strip handling devices for a press by means of which the strip stock is accurately located for a press operation after the proper amount of strip stock is presented.

Yet another object of the invention is the provision of tensioning elements in strip handling devices for a press which insure an even movement of the strip from its supply reel to the press thereby avoiding sudden fluctuations and unnecessary strains, buckling or kinking of the strip while in the apparatus.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a press provided with strip feed and control units embodying the present invention;

Fig. 2 is an enlarged sectional view of the strip stock reel and its support;

Fig. 3 is an enlarged side elevation of the stock withdrawing devices and speed control as viewed from the discharge side, parts being broken away to more clearly show the construction;

Fig. 4 is a top plan view of the mechanism shown in Fig. 3;

Fig. 5 is an elevation of the same as viewed from a position indicated by the line 5—5 in Fig. 3;

Fig. 6 is an enlarged end elevation of the press as seen from the feed-in side;

Fig. 7 is an enlarged sectional detail taken substantially along the line 7—7 in Fig. 6;

Fig. 8 is a top and front view of the press showing intermittent feed units and gauging devices for the strip stock;

Figs. 9 and 10 are sectional views of the press

on an enlarged scale taken substantially along the lines 9—9 and 10—10 in Fig. 8;

Fig. 11 is an enlarged sectional detail of the press notching device taken substantially along the line 11—11 in Fig. 10; and

Figs. 12 and 13 are enlarged sectional details of the press gauging device taken substantially along the line 12—12 in Fig. 10 and showing different steps in the gauging operation.

In the drawings which disclose a preferred embodiment of the present invention, the several units shown are indicated generally as a spool or reel strip support A, a withdrawing unit B, a press feeding unit C, a strip gauging unit D and a press E.

The reel support A is adapted to hold a spool of strip stock in a suitable position for easy withdrawal of the strip by the unit B which is continuously operated but at varying speed in accordance with the amount of strip stock required in the press. The feeding unit C is preferably intermittent in its action and feeds the work, i. e., the strip material, to the press E between the blanking or other working parts of the press. The gauging unit D acts upon the strip stock just before the working portion of each press stroke and accurately positions the stock each time for the blanking or other operation.

The strip stock, designated by the letter S, passes through both of the units B and C. A loop L is maintained in the stock between the two units to allow for any variation in the intermittent demand of the unit C or the continuous withdrawing action of the unit B. This loop L also allows for the unit B to regulate and control the speed of withdrawal from the spool on the support A in a manner to be described later.

The reel support unit A (see Figs. 1 and 2) besides holding or supporting a spool or reel 21 of strip stock S for withdrawal by the unit B also contains means for preventing an unrestrained rotation of the reel as the stock is unwound therefrom thus maintaining the proper tension on the stock. This unit comprises a drum 22 formed with an extended flange 27 on which the spool of stock rests when it is placed over the drum.

The drum 22 rotates on an axis inclined from the vertical such inclination being substantially that of the work feed table of the press which may be inclined in the usual manner to permit discharge of the work after blanking. The drum 22 is secured to a disc 28 which is formed with a centering boss 29 on which the flange 27 is centered.

The disc 28 is secured to the upper end of an inclined shaft 32 which is journaled in a bearing 34 the shaft being formed with an enlarged shoulder 35 which rests on the bearing. Bearing 34 is a part of a supporting base 36 which may rest on the floor or otherwise as desired.

The braking mechanism for preventing unrestrained rotation of the drum 22 and the reel or spool 21 carried thereby consists of a lever 41 (Fig. 2) pivotally mounted at its center on a pin 42 carried in the base 36. The lever 41 carries a brake shoe 43 at its upper end which bears on the inner surface of a depending cylindrical flange 44 of the disc 28. A stud 46 fixed in the base 36 passes loosely through a hole in the lower end of the lever, where a spring 47 is mounted. This spring is located on the stud and is adjustably held against the lever by a nut 48 and washer 49. The spring 47 tends to move the lever 41 counterclockwise (as viewed in Fig. 2) and this forces the brake shoe 43 against the flange 44 at a desired braking pressure, thereby restraining any free or uncontrolled rotation of the reel 21.

The withdrawing unit B (see Figs. 1, 3, 4 and 5) comprises a pair of inclined rotating rollers. 20 These co-act upon the strip S, which passes between them, as indicated in Fig. 4, to progressively pull the strip from its spool. One roller which may be termed the driving roller rotates on a fixed axis. It is driven by a motor, the speed 25 of which is governed by a regulating device that controls the motor speed in accordance with the amount of excess stock in the loop L.

The other roller may be termed a pressure roller. It is supported in a spring pressed cage 30 that provides a yielding pressure on that part of the strip S that is between the rollers. Provision is also made to relieve this pressure on the stock by manual separation of the driving and pressure rollers. This leaves the stock free between 35 the rollers.

The unit B is carried on a base 51 at an inclination substantially the same as that of unit A. This base may be mounted on a sub-base 52 which also supports the press E. A bearing bracket 53 is securely bolted to the base 51 and carries a substantial portion of the moving parts 40 of the unit.

The bracket 53 is provided with an upper bearing 55 (Fig. 3) and a lower bearing 56 in which 45 an inclined drive shaft 57 is journaled. The driving roller (designated by the numeral 58) is secured to the shaft 57 between the bearings 55, 56. It is formed with a flange 59 at its lower end which prevents the stock S from creeping off the 50 roller due to the inclination of the unit. The shaft and roller are driven in a manner which will presently be described.

The pressure roller (designated by the numeral 61) which co-acts with the driving roller 58 is mounted in the following manner. A bearing bracket 62 (Figs. 4 and 5) is bolted to the base 51 and carries a cage 63 which is pivotally connected to the bracket by a shaft 64. Shaft 64 is carried in bracket bearings 65. A cage hub 66 is mounted 60 on the shaft 64 and is slotted at both top and bottom to accommodate the bearings 65.

An upper cage arm 71 and a lower cage arm 72 extend radially from the hub 66 and provide a mounting for the roller. One arm is provided 65 with an upper bearing 73, the other with a lower bearing 74. A roller shaft 75 passes through these bearings and carries the pressure roller 61 which is secured to it between the cage bearings.

Spring pressure for holding the rollers in withdrawing engagement with the strip is applied to the cage 63 by springs 81 (Figs. 3 and 4) located adjacent the ends of the pressure roller which are mounted on rods 82 fixed in the stationary bracket 53. These rods pass through holes 83 70 in the cage arms 71, 72 and terminate in threaded

portions on which nuts 84 and washers 85 are mounted. This construction provides pressure adjusting means for the springs 81 which are held between the washers 85 and the arms of the cage 63.

A manual separation of the driving and pressure rollers is provided and this feature is used for adjustments or exchanges of the stock or mechanism. Such manual separation is made without disturbing the pressure adjustment of 10 the springs 81. An arm 91 (Figs. 4 and 5) extends radially from the middle of the cage hub 66 and terminates in a boss 92 on which one end of a link 93 is pivotally mounted. The other end of the link is pivotally and eccentrically connected 15 to a head 94 of a rock shaft 95.

The rock shaft 95 is journaled in bearings 96 formed in the bracket 62 and carries a handle 97 secured to it adjacent the upper bearing 96. Manual actuation of the handle through about 20 180° from the position as shown in Fig. 4 causes movement of the rock shaft head 94. By virtue of its eccentric connection to the head, the link 93 is drawn back and this draws with it the arm 91 which in turn moves the cage 63 through a 25 small arc sufficient to separate the pressure roller 61 from the stock S and from the driving roller 58.

Driving means for the withdrawing unit is preferably provided by a variable speed motor 101 (Fig. 3) which drives the withdrawing rollers 30 58, 61 through suitable gearing (see also Fig. 4). The motor 101 is bolted to the base 51 and carries a sprocket 102 keyed to its shaft 103. A chain 104 operates over the sprocket 102 and over a sprocket 105 which is keyed to a worm 35 shaft 106. Rotary motion from the motor is thus transmitted to a worm 107 secured to the shaft 106. The worm engages a worm wheel 108 fixed on the drive roller shaft 57 and thereby rotates the driving roller 58.

When the rollers 58, 61 withdraw the stock S from the unit A, they rotate in opposite directions, and at equal surface speeds. To obtain 40 this result, a gear 111, secured to the shaft 57 adjacent the bearing 56, meshes with a gear 112 45 secured to the shaft 75.

The speed of the motor 101 which governs the speed of stock withdrawal is under the control of a loop L of the stock between the units B and C. This loop indicates by its depth, normal shape 50 or shallowness that the demand of the blanking press is less than, equal to or in excess of the speed of withdrawal. A device for detecting slight variations in the loop shape or depth is used and this device will now be described in detail. It in 55 turn operates a motor speed control and thus functions in accordance with the demands of the blanking press.

Control contact with the loop L is made by a pair of detector rods 115 (Fig. 3) between which 60 the stock S passes and which are shifted in position by a change in shape of the loop. Their movement is transferred to a rheostat 116 which controls the motor speed and which is thus a part of the control device. A control bracket 117 65 is bolted to the extremities of the cage arms 71, 72 and provides a support for the detector rods 115. A pair of detector arms 118 are pinned to the ends of a rock shaft 119 which is journaled in 70 bearings 121 of the bracket 117.

A spacer bar 122 interposed between the free ends of the detector arms 118 holds them in spaced alignment. The extremities of the detector arms are formed as bosses 123 in which disc bearing blocks 124 are pivotally mounted. 75

The detector rods 115 are loosely mounted in these blocks and the latter act in some degree as side guides for the stock S as it passes between the rods.

5 The rheostat 116 (Figs. 3 and 4) is secured to a rheostat support 125 which is bolted to the control bracket 117. A rheostat shaft 126 is journaled in a bearing 127 formed in the support 125 and a gear 131 secured to the shaft adjacent the bearing meshes with a larger gear 132 pinned to the rock shaft 119. Swinging of the arms 118 due to change of shape of the stock loop L acting against the detector rods 115, is transmitted to the rheostat shaft 126 through the gears 132, 131.

10 Movement of the rheostat shaft 126 changes the setting of the rheostat 116 in the usual manner. The rheostat governs the speed of the motor 101 which rotates the withdrawing rollers 58, 61. In this manner the rheostat 116 cooperates with the detector rods 115 and the loop L to govern the speed of withdrawal of the stock S.

15 The press feeding unit C and the notching and gauging unit D are mounted on the press E (Fig. 8). They are directly actuated by moving elements of the press and so act in synchronism with its movements.

20 The press E as exemplified in Figs. 1, 6 and 8 may be and is herein shown as a triple blanking inclined press. A main arch frame 180 of the press may be mounted upon rear support columns 181 and front base members 182 carried by the sub-base 52. The main frame 180 comprises a frame table 183 extending up into two uprights or legs 184, 185. Spaced angle irons 186 (Figs. 1, 6 and 10) act as guide rails for the strip stock S as it passes into the press these rails being supported indirectly on the press frame and extending laterally from the press leg 184.

25 Three lower die members 187 (see Figs. 8 and 10) are bolted to an inclined bolster plate 188 which is secured to the frame table 183 and three cooperating punches or upper die members 189 are secured to an inclined punch plate 191. The punch plate is in turn secured to a press slide 192 which is slidably mounted in the arch frame legs 184, 185. These cooperating die members provide the active elements for the blanking or other press operations.

30 The slide 192 is actuated in the usual manner as by means of a pitman connecting with a crank element formed on a press crankshaft 193 as best illustrated in Fig. 8. This crankshaft is mounted in bearings formed in the arch frame 180 and receives its motion from a belt driven pulley and flywheel 194 secured on the shaft.

35 The strip feeding unit C comprises two pairs of intermittently driven rollers which engage the stock or strip S under pressure and feed it across the lower dies 187 between the strokes of the press. Such strip feeding is stopped after each advance of the strip and a braking action comes into play to prevent overfeed of the rollers. The pressure of the rollers on the stock is then relieved leaving the stock free to be acted on by the gauging unit D as will be described later.

40 Each pair of feeding rollers may be said to constitute elements of one of two sections of the strip feeding unit C. A first or feed-in section includes inclined parallel rollers 195, 196 (Fig. 6) and this section is located on the left

as viewed in Fig. 8. This pair of rollers feeds the strip stock S to the press.

45 The second or discharge section includes inclined parallel rollers 197, 198 (Fig. 8) and is located on the right side as viewed in that figure. Rollers 197, 198 discharge the scrap strip stock from the press after the press-formed or blanked articles have been removed. The rollers 195, 196 and the first section of the feed-in unit C will now be described.

50 The roller 195 (Fig. 6) is mounted on and secured to an inclined shaft 199 which is journaled in three spaced bearing blocks or brackets 200, 201, 202 mounted on a feed-in bracket 203 (see also Fig. 8) which is bolted on one side of the frame table 183. The roller 196 (Figs. 6, 8 and 10) is a pressure roller and is mounted on and secured to an inclined shaft 204 which is journaled in bearings 205 formed in a hinged cage 206.

55 Cage 206 is pivotally associated with the two bearing blocks 201, 202 by a supporting rock shaft 207. A cage hub 208 is mounted on the shaft and is slotted at both top and bottom to accommodate the bearing blocks, this construction being similar to the pressure roller 61 and its cage mounting.

60 Pressure for the feeding engagement of the rollers 195, 196 with the strip stock S is applied to the hinged cage 206 and through it to the pressure roller 196. This is a yielding pressure effected by springs 209 (Fig. 6) which are mounted on rods 210 extending out from and carried by the bearing blocks 201, 202. These rods pass loosely through openings in the arms 35 of the cage 206. Springs 209 are adjustably held under proper compression by washers 211 and nuts 212 the latter being threadedly engaged on the free ends of the rods.

65 Separation of the rollers after a strip has been positioned in the press is made at the time the press slide 192 moves down to perform the blanking or other operation and is brought about by rocking of the cage 206 and by lifting of the pressure roller 196 against the yielding action of the springs 209. It is done in the following manner:

70 The hub 208 (Figs. 6 and 10) of the cage 206 is extended laterally into an arm 213 the free end of which carries a stud 214 on which a roller 215 (see also Fig. 8) is rotatably mounted. A cam block 216 is carried on a horizontal bar 217 secured to the press slide 192 and when the latter moves down this cam block engages the roller 215 and pushes it out, at the same time rocking the cage 206 on its shaft mounting 207. This moves the pressure roller 196 away from the feeding roller 195 thus releasing the interposed strip stock S so that gauging (as by the gauging unit D) will take place before the punches 189 reach the strip.

75 The rollers 195, 196 are rotated in unison and for this purpose are interconnected by gearing which remains in driving connection even when the pressure roller 196 is moved away from the feed-in roller as just described. Such a gearing comprises a drive gear 221 (Fig. 6) secured to the shaft 199 which meshes with a driven gear 222 secured to the shaft 204.

80 Rotation of the rollers 195, 196 is intermittent and is brought about through the use of a pawl and ratchet unit actuated continuously from the crank shaft 193 as best shown in Figs. 6 and 8. The crank shaft 193 carries a spiral gear 225 which meshes with a spiral gear 226 secured to

an inclined shaft 227 which is at right angles to the crank shaft.

Shaft 227 is journaled in bearings 228, 229 formed in a bracket 230 bolted on the outside and 5 adjacent to the top of the arch frame leg 184. A crank disc 231 is secured to one end of the shaft 227 and carries a headed stud 232 on which the upper end of a connecting rod 233 is loosely mounted. The opposite end of the rod 233 loosely 10 mounted. The opposite end of the rod 233 engages a pin 234 projecting out from one face of a pawl and ratchet housing 235.

The housing 235 is loosely mounted on the feed-in roller shaft 199 outside of the bearing 200. This housing encloses a ratchet wheel 236 (Fig. 15 7) which is keyed to the shaft and the housing carries a spring pressed dog or pawl 237 which is mounted in a slide seat formed in a periphery of the housing. A spring 238 is used to back up 20 the pawl and this keeps its inner bevel face against 20 the teeth of the ratchet wheel.

As the housing 235 is oscillated back and forth relative to the center of the shaft 199, the latter is advanced in one direction with one part of the oscillation. On the return the pawl 237 slides 25 past the teeth of the ratchet wheel 236 thus advancing the shaft in a step by step movement. Movement of the shaft takes place as the connecting rod 233 moves up and with the rollers 195, 196 engaged and feeding the strip S.

30 Provision is made for abruptly stopping the rotation of the rollers 195, 196 and the feeding action on the strip stock therebetween so that there will not be an overthrow or uncontrolled movement. This is brought about by a braking device 35 that is cam actuated from the shaft 227 and that operates directly on the feed-in roller shaft 199.

This braking device comprises a brake drum 239 (Figs. 6 and 8) which is secured to the end 40 of the shaft 199 opposite the pawl and ratchet housing 235 and is adjacent and outside of the bearing 202. Brake shoes 240, 241 are pivotally connected together beneath the drum 239 and are held in a pair of parallel links 242 which have their ends connected to the bracket 203.

45 The free ends of the brake shoes are located on opposite sides of a rectangular end or head 243 of a pivot pin 244 (see also Fig. 10) which is mounted for oscillation in a bearing 245 formed in a bracket 246 bolted to the face of the arch frame leg 184. These free ends are tied together by a bolt 247 which extends loosely through an opening formed in one of the shoe ends this being in the shoe 241 and is threaded in the shoe 240. This bolt is also loose in the rectangular head 243 50 of the pin 244 and passes through the head. A lock nut 248 is threadedly secured to the end of the bolt.

60 A spring 249 is interposed between the end of the shoe 241 and the head of the bolt and keeps the ends of the brake shoes in engagement with the opposite faces of the rectangular head 243 of the pin. When these engaged faces of the head are straight with the faces of the ends of the 65 brake shoes, as illustrated in Fig. 10, the spring 249 holds the shoes clamped on the brake drum 239 this being their braking position.

The pivot pin 244 may be rocked in its bearing 245. When this takes place and when the engaged sides of the head of the pin are at an angle 70 to the faces of the ends of the brake shoes, the latter are separated further so that the clamping engagement between the shoes and the brake drum is nullified. This is the unbraking or free position and the brake drum 239 and the shaft 199 are then free to rotate.

This shifting of the pivot pin 244 is brought about by movement of an arm 251 secured to the pin intermediate its head and the bearing 245. The outer end of this arm is connected by a connecting rod 252 to the end of an arm 253 which 5 is pivotally mounted on a pin 254 carried in a bracket 255 bolted to the face of the frame leg 184.

The arm 253 is located adjacent the end of the shaft 227 and carries a cam roller 256 which 10 operates within a groove 257 of a face cam 258 and this cam is secured to the end of the shaft 227. The cam groove is of such a shape as to cause raising and lowering of the arm 253 and through the described connections with the other 15 arm 251, the pivot pin 244 is oscillated to further spread the brake shoes this being against the action of the spring 249. In point of time the braking device is out of operation when the rollers are rotating and when they are advancing the 20 strip S. The braking action on the other hand takes place immediately following such an advance movement of the strip stock by the rollers.

Before describing the second section of the strip feed-in unit C and the operation of the discharge rollers 197, 198 attention will be directed to the gauging device D and to the blanking or other die operations of the press.

The notching and gauging unit D may be divided into punch elements and die elements. 30 The punch elements are mounted on and move up and down with the punch plate 191. The die elements are stationary and are mounted on the die or bolster plate 188. The punch elements comprise a notching punch 261 (Figs. 8 and 11) 35 and a gauging and locating finger 262 (see also Figs. 12 and 13) pivotally mounted on a block 263 which is secured to the punch plate 191. Both notching punch and gauging finger are of similar cross section for a purpose that will be made 40 evident as the description proceeds.

The die elements comprise a notching die 265 and a gauging die 266 (Figs. 8 and 10) and both dies are mounted in a die block 268 which is 45 screwed to the bolster plate 188.

The strip S when released for gauging, as has already been described, is in an approximately correct blanking position relative to the press dies, the guide bars 186 on the side of the press preventing any wide misplacement of the strip. 50 In addition to this, one edge of the strip in its travel over the press table 183 is guided in a groove 269 (Figs. 10 and 11) formed in one edge of a guide bar 270.

The guide bar 270 is mounted on a pair of 55 spaced blocks 271 which are bolted to the bolster plate 188. Accurate positioning of the bar 270 relative to the blocks 271 is made by two setscrews 272 one of which is threadedly engaged in an upstanding lug of its associated block 271 and 60 its inner end abuts the rear wall of the guide bar. A locknut 273 threadedly secured on the setscrew holds it in its adjusted position.

When the ends of the bar 270 have been properly positioned by the setscrews 272 the bar is 65 locked in fixed position on the blocks 271 by bolts 274. There are two of these bolts, one for each block 271 and each bolt extends through a slot 275, formed in the block, and threadedly engages into the guide bar from below. When tightened 70 these bolts hold the associated ends of the bar in fixed position.

When the press slide is lowered this being immediately after the feed rollers 195, 196 of the feeding unit C have been separated to free the 75

strip, an initial shifting of the strip S into notch-ing position takes place. The notching punch 261 is formed with a lower projecting end 277 which passes into an opening formed in a stripper 5 plate 278 secured on the upper surface of the notching die 265. This projection 277 passes in front of the edge of the strip S and confines this strip between it and the guide bar 270, this initial locating and confining position being illustrated 10 in Fig. 11.

Continued downward movement of the notching punch 261 thereupon brings the punch into engagement with the strip and the punch then passes through the strip as it cooperates with 15 the notching die 265. This action cuts out a fragment of the strip and constitutes the notch-ing operation. The shape of the notch may be any desired form, a tapered or V-shape notch 280 (Fig. 10) being disclosed in the drawings. The 20 inclined sides of such a notch assists in the gauging action now to be described.

The distance between the center of the notching die 265 and the center of the gauging die 266 is equal to the distance of the step advance of the 25 strip S as effected by the feeding device C. Accordingly a notch 280 cut in the edge of the strip S at the die 265 at one stroke of the press is brought into approximate position over the gauging die 266 for the next stroke of the press. 30 The gauging finger 262 at the latter position therefore passes into the newly cut notch 280 and properly centers the strip S relative to the blanking die, this action at the same time centering the strip for the next notching operation.

35 It will be understood that when a strip S is first introduced into the press the notch is cut in the strip before its forward end has reached the gauging device. Such a first cut therefore is a preparation for the actual notching, gauging and 40 blanking of the strip which follows with the second and succeeding strokes of the press.

The gauging finger 262 (Figs. 8, 12 and 13) is pivotally mounted on a horizontal pin 285 carried in the block 263. This finger is directly 45 above the gauging die 266 and in the upper position of the slide 192 is held in a tilted position as shown in Fig. 12. This position is brought about by the action of a spring 286 which is mounted at one end on a pin 287 carried in the 50 gauging finger and at the opposite end on a post 288 extending down from the block 263. The upper face of the gauging finger is inclined at 289 and when tilted under the action of the spring 286 this inclined face engages against an 55 inclined stop wall 291 formed in the block 263.

As the press slide moves down the finger 262 enters the gauging die 266. An inclined wall 292 is formed on the lower end of the finger and this gauges against a similar inclined face 293 cut 60 in the wall of the opening of the notching die 266. When the surfaces 292, 293 first engage the inner side of the gauging finger 262 is in front of the edge of the strip S.

Continued downward movement of the press 65 slide with the gauging finger carries the latter further into the opening of the die 266 and slides the wall 292 over the inclined face 293 of the die. This action shifts the finger from its tilted position and brings it into a vertical position 70 as the spring 286 yields. This shifting of the finger forces the strip S toward the right (Figs. 12 and 13) so that its opposite edge is fully seated against the wall of the groove 269 of the guide bar 270.

75 It will be understood that this finger 262 upon

engaging the forward edge of the strip S passes into the notch 280 of the strip and as a finger comes into vertical position and moves down into the die 266 the finger not only gauges the strip laterally but also longitudinally. The cross section of the finger 262 being the same in shape as the notch 280 the inclined tapered walls of the finger fit closely within those of the tapered notch. Figure 13 illustrates the lowermost position of the gauging finger 262 and shows the 10 strip S fully held in its gauged position.

The lower end of the finger 262 (Fig. 8) is slightly below the lower end of the notching punch 261 and both of these members extend below the lower face of the blank punches 189. 15 Therefore the effect of a single downward stroke of the press slide 192 brings about the three steps of operation on the stock S in the following sequence: first, a gauging of the strip stock, then a notching of the same and finally the 20 blanking, forming or other operation of the punches 189 and dies 187.

After the blanking operation the principal part of the strip S has been removed and there is then left only a skeleton strip designated by the 25 letter K (Fig. 10). This skeleton K passes into and is discharged by the discharge rollers 197, 198 of the second section of the strip feeding unit C. Attention will now be given to this operation of the discharge rollers. 30

The roller 197 is mounted on an inclined drive shaft 300 (Figs. 8 and 9) which is journaled in bearings 301 carried in brackets 302 mounted on and secured to a discharge bracket 303. Bracket 303 is bolted on the side of the frame table 183 35 and thus supports all of the second section of the feeding unit C.

The roller 198 is a pressure roller and is mounted on and secured to an inclined shaft 304 which is journaled in bearings 305 formed in a 40 hinged cage 306. The rollers 197, 198 of the discharge unit and their mountings as well as manner of operation are substantially the same as that of the feeding rollers 195, 196.

The cage 306 is pivotally associated with two 45 bearings 307 formed by upward spaced projections formed in the brackets 302, this association being made by a supporting rock shaft 308. A cage hub 309 is mounted on the shaft and is slotted at both top and bottom to accommodate 50 the bearings 307.

Pressure for the feeding engagement of the rollers 197, 198 against the strip stock S is applied to the hinged cage 306 and through it to the pressure roller 198. This is a yielding pressure effected by springs 311 (Fig. 8) which are mounted on rods 312 (see also Fig. 9) extending out from and carried by the brackets 302. These rods pass loosely through openings in the arm of the cage 306. The springs 311 are adjustably 60 held under proper compression by washers 313 and nuts 314, the latter being threadedly engaged on the free ends of the rods.

The rollers 197, 198 like the rollers 195, 196 are periodically separated so that the skeleton 65 end K of the strip S is released each time the press slide begins its downward movement. Like the construction and operation of the first section of the feeding unit this separation is brought about by a rocking of the cage 306 and by a 70 lifting of the pressure roller 198 against the yielding action of the springs 311. It is done in the following manner.

The hub 309 of the cage 306 is extended laterally into an arm 315, the free end of which 75

carries a stud 316 on which a roller 317 is rotatably mounted. A cam block 318 is carried on a horizontal bar 319 secured to the press slide 192 directly opposite the bar 217. When the 5 press slide 192 moves down this cam block engages the roller 317 and pushes it out, at the same time rocking the cage 306 on its shaft mounting 308. This moves the pressure roller 198 away from the roller 195 and releases the skeleton end K of the strip.

10 The rollers 197, 198 are rotated in unison and for this purpose are interconnected by gearing which remains in driving connection even when the pressure roller 198 is moved away from the roller 197 as just described. Such a gearing comprises a drive gear 321 secured to the shaft 300 which meshes with a driven gear 322 secured to the shaft 304.

15 The rotation of the rollers 197, 198 is also intermittent and is synchronized with the rotation of the rollers 195, 196, a chain and sprocket connection joining the two parts of the feeding unit C for this purpose. The shaft 199 (Figs. 6, 8 and 9) of the first section roller 195 carries a sprocket 323 over which operates a chain 324. This chain also passes over a sprocket 325 secured to the shaft 300 and in this way the rotation of the rollers 197, 198 is brought about in the same time interval as the rollers 195, 196.

20 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

40 1. In a strip stock feeding mechanism, the combination of a press for working on the stock, a reel for holding a supply of the stock, means for withdrawing stock from said reel, means for feeding said withdrawn stock to said press, and means for controlling the speed of withdrawal in accordance with the amount of stock between said withdrawing and feeding means.

45 2. In a strip stock feeding mechanism, the combination of a press for working on the stock, a reel for holding a supply of the stock, means for continuously withdrawing stock from said reel, means for intermittently feeding said withdrawn stock to said press, and means for controlling the speed of withdrawal in accordance with the amount of stock between said reel and said press.

50 3. In a strip feeding mechanism, the combination of a press for working on the stock, a reel for holding a supply of the stock, a withdrawing unit for withdrawing stock from said reel, means for feeding said withdrawn stock from said unit and into said press, means associated with said withdrawing unit for maintaining an excess of stock in loop form between said withdrawing unit and said press, and means for operating said withdrawing unit in accordance with the amount of stock in said loop.

55 4. In a strip feeding mechanism, the combination of a press for working on the stock, a reel for holding a supply of the stock, a withdrawing unit for withdrawing stock from said reel, means for

feeding said withdrawn stock from said unit and into said press, means associated with said withdrawing unit for maintaining an excess of stock in loop form between said withdrawing unit and said press, and means operated by a change in shape of said loop for regulating the speed of withdrawal of the stock. 5

5. In a strip stock feeding mechanism, the combination of a reel for holding a supply of the stock, means for operating on said stock, a holder for 10 said reel, means for continuously withdrawing the stock from said reel to supply work for said operating means, a braking unit associated with said reel holder for maintaining a substantially uniform tension on said stock as it is withdrawn, and 15 means operating through said stock withdrawing means and varying with the supply of withdrawn stock not yet operated on by said operating means for varying the speed of withdrawal of the stock.

6. In a strip stock feeding mechanism, the combination of a press for working on the stock, a reel for holding a supply of the stock, rotating withdrawing rollers for withdrawing the stock from said reel, rotating feeding rollers for feeding said stock into said press, and means for regulating 20 the speed of rotation of said withdrawing rollers in accordance with the amount of stock between said withdrawing and feeding rollers.

7. In a strip stock feeding mechanism, the combination of a press for working on the stock, a reel 30 for holding a supply of the stock, rotating withdrawing rollers by which said stock is continuously withdrawn from said reel, an electric motor for operating said rollers, rotating feeding rollers by which said stock is fed to said press, a detector 35 associated with said withdrawing rollers and actuated by variation in the amount of stock between said withdrawing and feeding rollers, and an electric control associated with said motor and actuated by said detector for governing the rotation 40 of said withdrawing-rollers.

8. In a strip stock feeding, notching and gauging mechanism, a press for working on said stock, means for feeding said stock to said press, means for intermittently dissociating said feeding means 45 from said stock, notching means associated with the die elements of said press for preparing the stock for gauging, and gauging means operating on said prepared stock for positioning it relative to said die elements, said notching and gauging 50 means operating while said feeding means is dissociated from said stock.

9. In a strip stock feeding, notching and gauging mechanism, the combination of a press for working on stock, a reel for holding the stock, devices 55 for continuously withdrawing the stock at variable speeds, a braking unit applied to said reel for maintaining the stock under tension during withdrawal, feeding elements for feeding the withdrawn stock to said press, means for controlling 60 said withdrawing devices in accordance with the amount of stock between said withdrawing devices and said feeding elements, notching and gauging means for operating on the stock, said notching means producing successive wedge 65 shaped notches in the stock and said gauging means successively engaging the notches to accurately locate the stock both laterally and longitudinally in said press.
